UNITED STATES PATENT OFFICE.

GEORGE J. PIERCE, ALEXANDER PHEMISTER, AND ALFRED C. CONVERSE,
OF BOSTON, MASSACHUSETTS.

DESIGN FOR PRINTING-TYPE.

SPECIFICATION forming part of Design No. 12,235, dated April 26, 1881.

Application filed March 16, 1881. Term of patent 7 years.

To all whom it may concern:

Be it known that we, GEORGE JACKSON PIERCE, ALEXANDER PHEMISTER, and ALFRED COLLINS CONVERSE, citizens of the United States, residing at Boston, in the county of Suffolk and State of Massachusetts, have invented and produced a new and original Design for Printing-Types, of which the following is a specification, reference being had to the accompanying representation.

The description of our new type is as follows: The type are italic, and the name we give the style is "Norman Italic." The upright lines are all sloping, and these and the curved lines are light and of uniform weight. The horizontal lines, where joined to the upright lines, are filled in at the corners, both inside and out. In the numerals the figure 3

terminates in a curve above and below. The figures 5 and 9 bear respectively a curve at their lower ends. The figure 6 bears a curve at its upper end.

We claim—

The design for printing-types, as described and shown.
